UNITED STATES PATENT OFFICE.

JOHN A. PETRI, OF BROOKLYN, ASSIGNOR TO KOCH SONS & COMPANY,
OF NEW YORK, N. Y.

DESIGN FOR A BOOK OR ALBUM.

SPECIFICATION forming part of Design No. 19,527, dated December 24, 1889.

Application filed September 12, 1889. Serial No. 323,776. Term of patent 7 years.

To all whom it may concern:

Be it known that I, JOHN A. PETRI, a citizen of the United States, residing in Brooklyn, in the county of Kings and State of New York, have invented and produced a new and original Design for a Book or Album, of which the following is a specification, reference being had to the accompanying drawings, forming part thereof, in which—

10 Figure 1 represents two album-leaves as laid out flat, and Fig. 2 is a section of the same.

15 The leading feature of this design consists of a book or album the outline or configuration of the leaves of which is quadrilateral, with two edges inclined toward each other.

20 The lines *a* and *b*, bounding the back and front edges, are parallel, or nearly so, to each other, and the top and bottom lines *c d* are inclined or converge toward each other, the

angles 1 2 being obtuse and the angles 3 4 being acute. The corners may be clipped or rounding, as indicated by dotted lines at *f g*, without varying the leading feature of my design, and the shape of the picture-openings 25 *k l* also may be varied, and the openings will be omitted in some kinds of books.

The covers of the book are usually the same shape as the leaves, but slightly larger.

What I claim is—

30 In a design for a book, the design of the leaves, substantially as herein shown and described.

Signed by me this 9th day of September, 1889.

JOHN A. PETRI.
